(57) **CLAIM**

The ornamental design for a windshield lamp, as shown and described.

DESCRIPTION

FIG. 1 is a front perspective view of the windshield lamp design of the present invention;

FIG. 2 is a rear perspective view of the windshield lamp design of the present invention;

FIG. 3 is a front view of the windshield lamp design of the present invention;

FIG. 4 is a top view of the windshield lamp design of the present invention;

FIG. 5 is a bottom view of the windshield lamp design of the present invention;

FIG. 6 is a side view of the windshield lamp design of the present invention; and,

FIG. 7 is an opposite side view of the windshield lamp design of the present invention.

The broken line showing of the wire in FIG. 1 is included for the purpose of illustrating only and forms no part of the claimed design.

1 Claim, 4 Drawing Sheets
